UNITED STATES PATENT OFFICE.

JOHN THOMSON, OF NEW YORK, N. Y.

TUBULAR ZIGZAG CARBON ELECTRIC RESISTER.

1,318,031.

Specification of Letters Patent.

Patented Oct. 7, 1919.

Application filed October 7, 1918. Serial No. 257,218.

To all whom it may concern:

Be it known that I, JOHN THOMSON, a citizen of the United States, and a resident of the borough of Manhattan, city of New York, county and State of New York, have invented certain new and useful Improvements in Tubular Zigzag Carbon Electric Resistors, of which the following is a specification.

10 This is an invention in tubular, zig-zag, carbon, electric resistors, particularly adapted to heat articles placed in the interior thereof.

In the drawing,

15 Figure 1 is a composite front elevation and longitudinal center section of the resistor from the right and left-hand sides of the vertical center line A.

20 Fig. 2 is an end elevation either from the right or the left hand end of the resistor.

Fig. 3 is typical of a transverse section along any of the zig-zag slits, as the section on the line B; and

25 Fig. 4 is a fragmental longitudinal center section, revolved 90 degrees from that of Fig. 1 or Fig. 3, Fig. 4 being a section taken as on the center line C of Fig. 3 looking in the direction of the arrows.

30 The resistor D is formed of carbon, either graphitized or amorphous, and it is primarily molded as a cylindrical tube or a solid round rod, but in the latter case it is bored to produce a cylinder.

35 The next constructive step is to mill a series of transverse slots E from opposite sides, leaving connecting sections, as F and H, each of which is diametrically disposed from the other. In this wise, a "zig-zag" electric circuit, of restricted area, is formed 40 but with two notable differences from previous practice, namely:

The current passes in a circular path right and left, in parallel, as indicated by arrows 45 m, n Fig. 3, from one connecting section to another, and as the lineal length of the inner circumference of the resistor is manifestly less than that of its outer circumference the current density will be proportionately increased along the inner surface of the 50 bore.

As a consequence of transmitting the current in parallel, the cross-sectional area of each connector-section should be equal to that of the combined cross-sectional areas 55 of both of its connecting circular limbs. It is to be observed that, owing to the circular

traverse of the current as it passes from one pair of zig-zag limbs to another, an extensive lineal length of circuit may be obtained in a comparatively short resistor part. 60

The thermal effect, due to the increase of current density along the interior surface of this tubular resistor, may be illustrated by assuming that the lineal length of its outer circumference is, say 20 inches, while that 65 of the bore is 10 inches; consequently, both the development and emissivity of heat would be one hundred per centum greater along the interior than at the periphery. Hence, if the bore is utilized for heating an 70 article and the outside is insulated to minimize the escape of heat therefrom the conditions are unique for yielding efficient results. But, to utilize this tubular resistor, the carbon must be made immune to the 75 destructive effect of oxygen. This is accomplished in the following manner:

The carbon element having been formed, as in the manner already described, a supplemental and relatively thin-walled tube, as 80 J, is placed in the bore of the resistor, fitting snugly therein. The tube is preferably formed of fused aluminum oxid or crystalline silicon carbide, either of which is sufficiently non-conductive of electricity not to 85 short-circuit the carbon zigzags; is highly refractory; is an effective conductor of heat, and is non-reactive. Thereafter, the exterior of the resistor is surrounded by an airtight sheathing, of material such as fire-clay, 90 the outer limits of which are denoted as by the broken line P.

When the resistor is suitably set to be 95 electrically incited from a suitable source of electrical supply, such as is herein symbolically indicated by S, the resistor then becomes a highly efficient means for heating articles placed within its inner tube, especially so in the instance of relatively long metal articles of relatively small cross-section 100 as compared to the length, for example, of billets or rods, as T, Fig. 2.

While this tubular zig-zag resistor is peculiarly effective when used in the foregoing manner it may yet be employed to 105 heat gases flowing through its inner tube; or the latter may be dispensed with if or when it is desirable to radiate energy outwardly.

What I claim is:

1. A tubular, zig-zag, carbon, electric resistor having circular limbs which pass to

- and from their correlative connecting sections, whereby the transmission of electric current is in parallel from one to the other of any pair of said sections.
- 5 2. A tubular, zig-zag, carbon, electric resister having limbs arranged in pairs which pass to and from their correlative connecting sections, whereby the transmission of electric current is in parallel from one to the other 10 of any pair of said sections.
3. A tubular, zig-zag, carbon, electric resister having circular limbs which pass to and from their correlative connecting sections, whereby in the electric transmission 15 of energy from one to the other of any pair of said sections the current density is the greater along the linner surface of the bore of the resister.
4. A tubular, zig-zag, carbon, electric resister having a supplemental inner tube 20 formed of material immune to oxidization.
5. A tubular, zig-zag, carbon, electric resister whose exterior is heat-insulated and whose interior bore contains a supplemental tube immune to oxidization. 25
6. A tubular, zig-zag, carbon, electric resister whose exterior is heat-insulated, whose inner bore contains a tube immune to oxidization and which also serves as a receptacle for articles to be heated. 30

This specification signed and witnessed this 10th day of September, A. D. 1918.

JOHN THOMSON.
